Primary Examiner — Cynthia Ramirez*Assistant Examiner* — Tamara L Hahn(74) *Attorney, Agent, or Firm* — Ruggiero McAllister & McMahon LLC(57) **CLAIM**

The ornamental design for a heated air hair brush, as shown and described.

DESCRIPTION

FIG. 1 is a front perspective view of an ornamental design for a heated air hair brush according to the present invention; FIG. 2 is a top plan view of the heated air hair brush of FIG. 1;

FIG. 3 is a bottom plan view of the heated air hair brush of FIG. 1;

FIG. 4 is a left side elevational view of the heated air hair brush of FIG. 1;

FIG. 5 is a right side elevational view of the heated air hair brush of FIG. 1;

FIG. 6 is a rear elevational view of the heated air hair brush of FIG. 1; and,

FIG. 7 is a front elevational view of the heated air hair brush of FIG. 1.

The broken lines in the drawings depict portions of the heated air hair brush which form no part of the claimed design.
